United States Patent Office.

FRANZ WAGNER, OF NEW YORK, N. Y., ASSIGNOR TO HIMSELF, JOHN W. CRUMP, AND WILLIAM A. LYNCH, OF SAME PLACE.

Letters Patent No. 99,266, dated January 25, 1870.

IMPROVEMENT IN LIQUID-METERS.

The Schedule referred to in these Letters Patent and making part of the same.

To all whom it may concern:

Be it known that I, FRANZ WAGNER, of New York, in the county and State of New York, have invented a new and useful Improvement in Water-Meters; and I do hereby declare that the following is a full and exact description of the same, reference being had to the accompanying drawings, and to the letters of reference marked thereon.

Figure I represents a horizontal section of my improved water-meter;

Figure II is a vertical section of the valve-chamber and valves;

Figure III is a vertical section of the cylinders and passages between;

Figure IV is a section of the valve-chamber at the line *x*, Fig. II; and

Figure V is a section of the valve-chamber and valve, at the line *y*, Fig. II.

Similar letters represent similar parts in all the figures.

This invention relates to a meter for measuring water or any other fluid; and consists of two pistons, working in suitable cylinders, connected, through suitable piston-rods, with a double circular valve, which, as the pistons assume their reciprocating motion, by the fluid acting upon the same, cause this circular valve or valves to rotate, and thereby change the direction of the fluid.

A A' represent the cylinders, into which the pistons B B' are fitted.

These cylinders have the valve-chest C attached to one end.

The valves D D', with their dividing-disk E, are attached to a common shaft or spindle, F, having, at each end, a crank, *a a'*, attached, to which the piston-rods *b b'* are connected, at an angle of about ninety degrees, more or less, to each other.

The valves D D' and the dividing-disk E, are ground into their respective seats *J J'* in the valve-chest C, and the valve-chest C is arranged with suitable passage-ways *n n'*, forming a communication between the inlet or supply-pipe G and the interior of the valves D and D', as well as with suitable passage-ways *m m'*, forming a communication between said valves and the discharge-pipe H; and further, this valve-chest C has suitable passage-ways *v v'* arranged, connected with the passage-ways *w w'*, forming a communication between the ends of the valves D D' and the ends of the cylinders A A', behind their respective pistons, while the outer ends of said valve-chest C are in direct communication with the forward ends of the cylinders A A' by the passages *p p'*, and through which said passages *p p'*, the piston-rods *b b'* pass, to connect with the cranks *a a'*, to give the necessary and required rotation to the valves D D'.

The registering-apparatus may be placed on either end of the valve-chest, and may be operated by a suitable lever, connected with the crank-pin of the crank *a* or *a'*.

The valves D and D' are constructed with two chambers, *r r'* and *s s'*, respectively, each of which connects either with the opening in communication with the supply-pipe and one or the other end of the passage leading to the cylinder, or with the opening in communication with the discharge-pipe, and the one or the other end of the passage into the cylinder, according to the position of said valve.

When the pistons occupy the position represented in the drawing, the fluid before the piston B will pass through the chamber *r*, in the valve D, into the passage *m* and discharge-pipe H, while the fluid from the supply-pipe G will pass, through the passage-way *n*, into the chamber *r'* in the valve D, and through the end of said valve into the passage *v*, through the passage *w*, into the cylinder A, behind the piston B, acting upon the same, so as to propel said piston in the direction indicated by the arrow. At the same time, the fluid from the supply-pipe G passes through the passage *n'*, through the chamber *s'* in the valve D', through the end of said valve into the passage *v'*, through the passage *w'* into the cylinder A', behind the piston B', acting upon the same, so as to propel said piston in the direction indicated by the arrow, and, at the same time, assist the passage of the crank *a*, to which the piston B is connected, over the centre, while the fluid before the piston B' will pass through the passage *p'*, the chamber *s* in the valve D', through the passage *m'* into the discharge-pipe H.

When the pistons reach the end of their stroke, the position of the respective valves is thereby changed, and the fluid passes in the contrary direction.

By these means, a fluid-meter is obtained, wherein the valves are self-operating, without the assistance of any extra lever or springs, and which operates with very little pressure, and independent of any head under which the fluid enters to or discharges from the meter. All the friction created by the working-part is easily overcome, and no fluid can pass through the meter unless it is measured.

This meter may be placed in the ground-floor of a building, and it will indicate the water drawn from any of the faucets in the house.

What I claim as my invention, and desire to secure by Letters Patent, is—

1. The arrangement of the rotating valves D D', connected, through suitable rods *b b'*, with two reciprocating pistons B B', and operating in the manner and for the purpose substantially as described.

2. The rotating valves D D', with their respective chambers *r r'* and *s s'*, in combination with the passage-ways *n n'*, *m m'*, and *v v'*, and communicating, through the passages *p p'* and *w w'*, with the ends of the cylinders A A', the whole being arranged substantially as and for the purpose set forth.

FRANZ WAGNER.
